US00D876140S

(12) **United States Design Patent** (10) **Patent No.:** **US D876,140 S**
(45) **Date of Patent:** **** Feb. 25, 2020**

(54) **SEATING ARRANGEMENT**

(71) Applicant: **Steelcase Inc.**, Grand Rapids, MI (US)

(72) Inventors: **Gordon J. Peterson**, Rockford, MI (US); **Robert J. Battey**, Middleville, MI (US); **Gary Lee Karsten**, Wyoming, MI (US); **Mark Vander Veen**, Hudsonville, MI (US); **Nickolaus William Charles Deever**, Holland, MI (US); **Peter A. Boeckel**, Hong Kong (HK)

(73) Assignee: **Steelcase Inc.**, Grand Rapids, MI (US)

(**) Term: **15 Years**

(21) Appl. No.: **29/680,712**

(22) Filed: **Feb. 19, 2019**

Related U.S. Application Data

(63) Continuation of application No. 29/605,422, filed on May 25, 2017, now Pat. No. Des. 851,418.

(57) **CLAIM**

The ornamental design for seating arrangement, as shown.

DESCRIPTION

FIG. 1 is a perspective view of a seating arrangement embodying the present invention;

FIG. 2 is a front elevational view of the seating arrangement; FIG. 3 is a first side elevational view of the seating arrangement;

FIG. 4 is a rear elevational view of the seating arrangement; FIG. 5 is a second side elevational view of the seating arrangement;

FIG. 6 is a top plan view of the seating arrangement; and, FIG. 7 is a bottom plan view of the seating arrangement.

1 Claim, 7 Drawing Sheets
